UNITED STATES PATENT OFFICE

163,398

WEATHER FORECASTER

Howard R. Lippert, Toledo, Ohio

Application November 10, 1947, Serial No. 142,417

Term of patent 14 years

(Cl. D52—7)

To all whom it may concern:

Be it known that I, Howard R. Lippert, a citizen of the United States of America, residing at Toledo, in the county of Lucas and State of Ohio, have invented a new, original, and ornamental Design for a Weather Forecaster, of which the following is a specification, reference being had to the accompanying drawing, forming part thereof.

Fig. 1 is a front elevation of a weather forecaster, showing my new design; and

Fig. 2 is a side view thereof from the right of Fig. 1.

The characteristic features of my design reside in the portion shown in full lines.

I claim:

The ornamental design for a weather forecaster, substantially as shown and described.

HOWARD R. LIPPERT.
